FUEL PUMP

Carl F. High, Flint, Mich.

Application April 22, 1937, Serial No. 138,390

11 Claims. (Cl. 123—139)

The invention relates generally to fuel pumps for internal combustion engines and more particularly to the control means associated with such pumps for governing the ultimate fuel-air ratio of the mixture supplied to the engine.

When a fuel pump is employed to feed small, accurately measured charges of fuel for the individual cylinders of an internal combustion engine, the relative proportioning of the fuel and air supply becomes an important consideration in obtaining efficient engine performance at all speeds, and it is customary, therefore, to provide a common inter-related control means for varying the fuel charge and air supply in an efficient relation throughout the range of engine speeds. In attaining an efficient fuel-air ratio, such a common inter-related control means establishes a definite relationship between the actuation or movement of the fuel volume control and the air volume control throughout the range of engine speeds, and it is found that variations in air pressure incident to altitude changes of an aircraft engine result in a detrimental fuel-air unbalance.

An important object, therefore, of the present invention is to provide a fuel pump for internal combustion engines embodying a new and improved control means whereby an efficiently proportioned air and fuel supply may be provided for atmospheric conditions encountered at any altitude of engine operation.

Another object is to provide such a device wherein a new and improved coordinated mechanism of a simple character for varying the fuel and air supply to the engine may be adjusted manually to provide for changes in atmospheric and barometric conditions, and efficient fuel-air ratio throughout the range of engine speed.

A further object is to provide a single throttle connection for regulating valves controlling both fuel and air supplies to an engine which comprises a common lever connection between the valves and an adjustment separately operated for varying the effective length of the lever arm connection to alter the extent of the opening of one with respect to the other so as to change the ratio of fuel to air supplied to the engine as a result of normal throttling.

More specifically, the present invention has for its object the provision of new and improved fuel and air control mechanism of this character embodying means whereby the pilot may, when different atmospheric conditions are encountered during flight, adjust the mechanism to deliver throughout the range of engine speeds, a properly coordinated supply of fuel and air.

Other objects and advantages will become apparent when considered in view of the following description taken in connection with the accompanying drawings, in which:

Fig. 1 is a view illustrating a preferred embodiment of the invention with the fuel pump shown in vertical central section. 5

Fig. 2 is a detail view of the fuel valve and its control cam.

Fig. 3 is a fragmental view of the control means of Fig. 1 with the parts thereof in different adjusted position. 10

Figs. 4 and 5 are sectional views taken along the line 4—4 of Fig. 3 and illustrating a part of the control means in different positions of adjustment. 15

For purposes of disclosure, I have illustrated in the drawings and will hereinafter describe in detail the preferred embodiment of the invention, with the understanding that I do not intend to limit my invention to the particular construction and arrangement shown, it being contemplated that various changes may be made by those skilled in the art without departing from the spirit and scope of the appended claims. 20

In the form chosen for disclosure herein, the invention is intended and adapted for use with the internal combustion engine of an aircraft, and is embodied in a fuel and air supply system wherein a variable output fuel pump 10 and an air intake manifold 11 provide an efficiently coordinated, adjustable supply of fuel and air for the engine under the control of a common accelerator connection 12. 30

The fuel pump 10, as illustrated herein, is of the suction metering type having a generally cylindrical casing 13 with a plurality of individual pumping units, disposed concentrically of its axis in the lower end of the casing, and actuated by a rotatable cam plate 14 housed in a chamber 15 in the upper portion of the casing. In the lower portion of the casing 13, and in the space within the annular row of pumping units, a relatively large fuel chamber 16 is provided to supply fuel for all of the pumping units. 35

Each pumping unit preferably comprises a piston 17 reciprocable and oscillatable in a cylindrical bore 18 formed in the wall of the casing 13 at the side of the chamber 16, all of the bores being closed at their lower ends by plugs 19 held in place by a bottom plate 19, and all of the bores terminating at their upper ends in a chamber 15' formed in the casing below and partially separated from the chamber 15. The pistons 17 extend upward beyond the termination of the bores 40

45

50

55

into the upper chamber 15 to provide for operative association of the pistons 17 with the actuating cam plate 14. At a point above its closed lower end, there is an inlet to each cylinder 18 from a radial duct 20 located each in its respective arm 46 of a spider-like internal frame. Spaced circumferentially at approximately 90° from the inlet is an outlet duct from the cylinder, positioned so that it is invisible in the views of the device here presented. From the lower end of each piston 17 a central bore 21 extends upwardly to a lateral extension or port 22 opening through the side of the piston 17 so that the clearance space of each cylindrical bore may communicate first with the inlet duct 20 to receive a charge of fuel and then with the outlet to discharge the fluid as the piston is periodically reciprocated and oscillated.

As shown in Fig. 1, each piston 17 has a cam shoe 23 engaging therewith at the upper end through the agency of a ball and socket joint 24. An expansive spring 25, surrounding the piston within the chamber 15' and acting between the casing and a flange 26 at the upper end of the piston, may be operable to urge the cam shoe 23 into bearing relation with an actuating cam surface 27 on the cam plate 14. Thus in rotation of the cam plate about the axis of the casing 13, the pistons are reciprocated in succession, a stop plate 28 being employed, if desired, to accurately gage the end of the upward or suction stroke. Another purpose of the cam plate 14 is to impart timed oscillation to the pistons 17. A cam finger or follower 30 is accordingly provided which projects rigidly from the piston 17 through a suitable radial slot (not shown) in the cam shoe 23, and upward into a cam groove 31 in the lower face of the cam plate 14. The follower track thus formed by the groove is distant from the axis of rotation by a variable amount, so proportioned that a periodic sequence of rotation is given to the piston. Details of this portion of the structure are more clearly set forth in my Patent No. 2,060,076, issued November 10, 1936. The cam surface 27 and the cam groove 31 are so formed and related that the port 22 registers with the inlet duct during the suction stroke and with the outlet duct during the discharge stroke of the piston.

Cam plate 14 is preferably journaled in the casing 13 by an axially hollow shaft 14' formed integrally with the plate 14 and extending upwardly therefrom into an upwardly projecting axial bearing hub 32 formed at the top of the casing. A friction bearing 33 and a combined radial and thrust bearing 34 in the bearing hub 32 serve to support the upper and lower portions respectively of the hollow shaft 14'. The inner race of the bearing 34 is supported on a shoulder 14'' of the hollow shaft 14', while the outer race is clamped between the casing 13 and an annular internally flanged ring 34' secured to the casing by bolts 34'' preferably concealed by an annular plate 13'. Extending through and journaled in the hollow shaft 14' is a drive shaft 35 which drives the cam plate 14, in a forward direction only, through a single-position, one-way clutch 36. This one-way clutch is described in greater detail and is claimed in my copending application Serial No. 124,063, filed February 4, 1937. Outside of the bearing hub 32, the drive shaft 35 has a fixed flange 37 riding against the end of the bearing 33, while at its lower or inner end an expansive spring 38 surrounds the drive shaft 75 and acts between a collar 38 fixed on the shaft

and the cam plate 14 to hold the plate 14 in the vertical position determined by the bearing 34.

In the form illustrated herein, fuel is drawn from a fuel supply tank 40 and fed to the chamber 16 by a fuel feed pump 41 which is preferably mounted within the pump casing 13 so as to be actuated by the drive shaft 35. Thus the feed pump 41 has its casing 41' fixed axially of the casing 13 below and in alignment with the shaft 35 so that its rotor 41'' may be driven from the shaft 35 by a coupling 42. The casing 41' extends through the top wall 43 of the chamber 16, and has its outlet 16' discharging into the chamber 16, while its intake 44 is formed through an enlarged or thickened portion (not shown) of the wall 43 as a continuation of a pipe leading from the fuel tank 40. Particulars of the feed pump 41 and its relationship to the other elements of the device are shown and described in detail in my copending application Serial No. 90,056, filed July 11, 1936. Beneath the pump 41 and in the supply chamber 16 lies the spider-like distributing member 46 containing the inlet duct 20 previously referred to, which has a central distributing chamber 47 at the hub from which ducts 48 radiate to communicate with the inlet ducts 20 leading to the several pump cylinders. Threaded upwardly into the hub of member 46 is a plug 49 formed with a vertical metering passage 50 communicating at its upper end with the chamber 47 and at its lower end with the supply chamber 16 so as to pass fuel from the source of supply to the radiating ducts 48.

The quantity of fuel supplied to the pumping units is controlled by a manually actuated tapered valve or metering pin 51 disposed in the metering passage 50. The metering pin 51 is preferably supported on a piston 51' slidably vertically within a sleeve-like downward extension 49' of the plug 49. Above the upper level of the piston 51' transverse ports 53 in the plug 49 provide for communication between the passage 50 and the fuel supply chamber 16. An inverted cup-shaped member 45' may be secured between the hub and a shoulder on the plug 49 with the skirt portion thereof extending over but spaced from the ports 53. To provide for longitudinal movement of the pin for varying the quantity of fuel metered thereby, a spring 54 surrounds the extension 49' and acts against a bottom flange 51'' of the piston 51' to maintain the lower end of the piston in contact with an actuating control cam 56. Preferably the cam 56 is carried within the chamber 16 on a hollow horizontal shaft 57 so that by rotation of the cam, the valve or metering pin 51 may be opened or closed as desired. On the projecting outer end of the shaft 57 an arm 58 is mounted, the arm 58 being connected by means of an angle fitting 76 to a link 59 pivoted upon an actuating arm 60 of an air control valve 61 which controls the air intake manifold 11. The arm 60 is connected to and actuated by the manually operable accelerator connection 12, so that the fuel metering pin and the air control valve are opened or closed in unison.

In maintaining the most efficient quantity relationship between the fuel and air throughout the range of adjustment of the fuel and air valve means, the valves of the present embodiment are relatively simple in form and the requisite variation in relative movement of the several parts is obtained through the conformation of the effective cam surface of the cam 56 which is for this reason termed the "fuel-air cam" of the mechanism.

To secure accurate suction metering of the fuel past the needle valve or metering pin 51, the feed pump 41 is constructed so as to feed fuel in excess of the total requirements of the fuel pumping units, and a uniform pressure is maintained in the chamber 16 by a constant pressure relief valve 62 located in a by-pass line 63 leading from the chamber 16 to the fuel tank 40. As shown in Fig. 1, the by-pass line 63 is connected to a valve chamber 64 formed by an upwardly extending vertical bore in the side wall of the casing 13, there being a valve port 65 axially located in the upper end of the bore and communicating with the chamber 16 so as to be adapted to be opened and closed by vertical movement of a valve 62 in its chamber 64. Thus the pressure of the fuel in the supply chamber 16 acts on the exposed upper end of the valve 62 with a tendency to unseat or open the same, this valve opening action being controlled by a spring 66 located in the chamber 64 and acting between the valve 62 and a plug which extends through the bottom plate 19 and is threaded into the lower end of the chamber 64.

Since the air valve 61 and the fuel metering valve 51 are actuated in unison, it is found that in the operation of the engine in an aircraft, the changes in air pressure incident to changes in altitude cause variation in the amount of air fed for a particular positioning of the two valves, with the result that an unbalance of the fuel-air ratio causes inefficient engine operation. The present invention contemplates and provides means whereby the pilot may, at any time during flight and in accordance with the altitude, correct or adjust the relative operative relationship of the fuel and air valves so that throughout their range of movement by the accelerator 12, the proper proportion of fuel and air will be supplied to the engine. Such corrective adjustment is, in the present embodiment, obtained through manually effected variation of the operating connection between the accelerator 12 and the fuel valve 51, so that for any given movement of the air valve 61, the corresponding movement of the fuel valve 51 may be adjusted. Preferably such adjustment is effected by varying the effective length of the control arm 58 of the fuel pump 40, and in order that required adjustment may be made during flight, and without interference with the normal operativeness of the accelerator and the operating connections therefrom, the adjusting means is actuated by an element 70 (Fig. 4) which is shiftable axially of the cam shaft 57 by means of a Bowden cable 71. The Bowden cable 71 may, of course, have its other end connected to a reciprocable operating knob (not shown) located conveniently and in a conventional position on the instrument panel so as to be accessible and operable in accordance with principles familiar to most pilots.

Below the plate 19 at the bottom of the casing a hollow cap 19' is attached which is recessed for reception of the cam 56 and the contacting end of the piston 51'. As illustrated in Figs. 4 and 5, the cam shaft 57 is tubular in form and is journaled in the cap 19' by a sleeve bearing 72, and the adjusting element 70 takes the form of a rod slidably mounted in the tubular cam shaft. On the projecting end of the cam shaft 57, a supporting or mounting member 73 is fixed, said member having a mounting sleeve portion 74 surrounding and secured to the shaft 57 and a second sleeve portion 75 integrally formed at one side of and disposed at right

angles to the mounting sleeve portion 74 so as to form a slideway in which the arm 58 may be moved longitudinally in a direction transverse to the axis of the cam shaft 57. At one end of the arm 58 the angle fitting 76 is pivoted by a pin 77, and one end 78 of the link 59 is screw threaded into the angle fitting. Thus by sliding the arm 58 longitudinally within the sleeve 75, the effective length of the arm (that is, the radial distance between the pivot 77 and the axis of the cam shaft 57) may be adjusted. Such adjustment is effected by longitudinal movement of the axially slidable rod 70, and to this end the rod 70 is connected by means of a link 80 to the other end of the arm 58.

In order that the link 80 may, in one position of the slide rod, stand parallel and adjacent to the arm 58, the end of the link 80 which is connected to the arm 58 is formed with a right angle extension 81 through which a pin 82 extends to pivot the link 80 and the arm 58 together. From its pivotal connection 82, the link extends past one side of the sleeve 74, and at its other end is connected by a pivot pin 83 to a lug 84 which extends from a head 85 fixed to the end of the slide rod 70. The Bowden cable 71 is in the present instance attached to the head 85 by a swivel joint 86. As best seen in Figs. 4 and 5, the joint is formed by a member 86' at one end threaded to the 20 Bowden cable and reduced at the other end to be received in a recess in the head 85. The reduced portion and the recess are formed with complementary grooves 86'' in which pins 86''' are inserted in well known manner.

Preferably, the withdrawal of the adjusting or slide rod 70 by means of the Bowden cable 71 is opposed by a yielding means forming a part of the adjustable assembly carried by the cam shaft 57. In the present instance, this means 30 comprises an expansive coil spring 87 surrounding the arm 58 between the bearing sleeve 75 and a flange formed on the arm 58 adjacent to the pivot pin 82. The spring 87 may actually serve to return the arm 58 to its shortened 40 relation of Fig. 3 when the cable 71 is released, or it may, as in the present instance, be of such a strength as to act in the nature of a counterbalance to facilitate a return movement actually initiated by force applied through the cable.

When the slide rod 70 is in the position shown in Figs. 3 and 4, the toggle link 80 is positioned parallel to the arm 58 and the arm is, therefore, in its fully retracted or shortened position wherein the arm has its minimum effective length. Hence the movement of the accelerator 12 to open fully the air valve 61 will operate also to open the needle valve to its fully retracted position with the result that the maximum pump output will be fed to the engine. This adjustment 50 adapts the fuel feeding system for operation of the engine at substantially sea level conditions wherein the maximum atmospheric pressure feeds air into the intake at the maximum rate.

As the engine is carried by a plane to a higher altitude, there is a notable decrease in air pressure which results in less combustible air being drawn into the engine at the intake. To compensate for the change, the effective length of 70 the arm 58 is increased by endwise withdrawal of the slide rod 70 so as to reduce the fuel valve opening in proportion to the air valve opening. In the position of maximum extension of the effective length of the arm 58 (shown in Figs. 1 75

- and 5, and indicated by dotted outline in Fig. 3), the maximum opening of the air valve 61 produces only slightly over half the movement of the cam 56. Therefore, the amount of fuel fed to the engine is reduced to correspond to the reduced air supply, and similar adjustments may be made to produce the correct relationship of the fuel and air valve movements for any intermediate altitude.
- 10 In connection with the proportioning and arrangement of the adjustable linkage, it is to be noted that the pivot pin 83, in an adjusting movement while the air and fuel valves are in their idling positions, is shifted along a line which is substantially perpendicular to the longitudinal axis of the link 59. Because of this relationship, the adjustment of the arm 58 does not change the low speed or idling position of the fuel valve, but is effective to produce relatively reduced fuel valve opening only when the accelerator is positioned for speeds above the idling speed.

From the foregoing description, it will be apparent that the present invention provides a fuel and air feeding apparatus capable of adjustment during flight to correct for changes of altitude so as to furnish an efficient proportion of fuel and air. It will also be evident that the adjustment is accomplished by means of a simple and rugged character, and that the manually operated actuating element thereof is adapted for mounting and actuation in accordance with principles familiar to most pilots.

I claim as my invention:

1. In a fuel and air supply system for an internal combustion engine, the combination of an air intake having a control valve mounted on a rock shaft, a fuel pump for supplying fuel to the engine cylinders and having means for varying the fuel output of the pump including an operating rock shaft, an operating arm on each of said rock shafts, a link pivoted at its opposite ends to said arms, means for shifting said link at one of its ends toward and away from the axis of the adjacent rock shaft to vary the effective length of the arm at said end, and means for actuating said shifting means including an element shiftable axially of said adjacent rock shaft.

2. In combination with the air intake of an internal combustion engine, a valve for controlling the air intake, a rock shaft mounting said valve, a first operating arm on said rock shaft, a fuel pump for supplying fuel to the engine, means for varying the fuel output of said pump including a second rock shaft through rocking movement of which the output of fuel is varied, a bearing member fixed to said second rock shaft, bearing means on said member providing a slideway extending generally radially with respect to the axis of said second rock shaft, a second operating arm slidable on said slideway to vary the position of the ends of said second arm with respect to said shaft axis, a link connected between said first operating arm and one end of said second arm, a slide member mounted on said second rock shaft for movement longitudinally thereof, and a link pivoted at its opposite ends to said slide member and to said second operating arm at a point eccentric to the slide member.

3. In combination with the air intake of an internal combustion engine, a control valve for said intake having an operating arm, a variable output fuel pump connected to supply fuel to the engine and having output control means including an actuating arm, a link pivotally connected at its opposite ends to said arms to effect simultaneous

rocking movement of the arms, and means for varying the effective length of one of said arms with respect to its pivotal connection with said link.

4. In combination with the air intake of an internal combustion engine, an air intake valve having an operating arm, a fuel pump having means for varying the fuel output including a rock shaft, a link pivoted at one end to said valve operating arm, a second operating arm extending transversely of said rock shaft and adjustable to vary its effective length relative to the axis of said shaft, said link being pivoted at its other end to one end of said second arm, an adjusting member mounted on said rock shaft for movement longitudinally thereof, and an operating connection between said adjusting member and said second arm for varying the effective length of said second arm as said adjusting member is shifted longitudinally of the rock shaft.

5. Apparatus of the character described comprising, in combination, an air intake for an internal combustion engine, an air intake valve having an operating arm, a fuel pump having means for varying the fuel output including a rock shaft, a link pivoted at one of its ends to said operating arm, means connecting the other end of said link to said rock shaft eccentrically thereof to impart rocking movement to said shaft when said link is actuated, adjusting means for varying the degree of eccentricity of said last mentioned connecting means, an adjusting member mounted on said rock shaft for movement longitudinally thereof and operable in such movement to actuate said adjusting means to vary the eccentricity of said connecting means, and an operating means connected to said adjusting member axially thereof.

6. In a fuel and air supply system for internal combustion engines, the combination of an air intake having an air control valve movable between idling and wide open positions, a fuel pump for supplying fuel to the engine, fuel control means for varying the fuel output of said pump including a metering valve movable between idling and wide open positions, an operating cam for actuating said metering valve, and means for actuating said cam, a manually operable accelerator means connected to said air valve and said fuel control means for actuating the same to vary the engine speed, and manually actuated adjusting means operable upon a part of said fuel control means to vary the control movement of said metering valve with relation to said air control valve while maintaining the same relationship of the idling positions of said valves.

7. In a fuel and air supply system for the internal combustion engine of an aircraft, the combination of an air intake having a control valve, a fuel pump for supplying fuel to the engine cylinders and having a fuel valve for varying the fuel output of the pump, an accelerator having operating connections to both of said valves for opening and closing said valves in predetermined relation to vary the engine speed, and means for adjusting one of said connections during flight to vary said predetermined relation of the fuel and air valves.

8. In a fuel and air supply system for internal combustion engines, the combination of an air intake having an air control valve mounted on a rock shaft, an operating arm on said rock shaft, a fuel pump for supplying fuel to the engine, fuel control means for varying the fuel output of said pump including a shiftable ele-

ment, an operating cam for actuating said shiftable element, and a shaft carrying said cam and having an operating arm, a link connecting said arms, a manually operable accelerator connection for actuating said arms to vary the engine speed, and a manually adjustable altitude compensating means including and operable through an element movable longitudinally of said cam-supporting shaft to vary the controlling movement of said shiftable element with relation to the movement of said air control valve.

9. In combination with the air intake of an internal combustion engine, an air intake valve having a supporting shaft and an actuating arm, a fuel pump for supplying fuel to the engine cylinders, fuel control means for varying the fuel output of said pump including a shiftable element, a shaft, a cam supported on said shaft for operating said shiftable element, and an arm 20 on said shaft, a link connecting said arms, a manually operable accelerator connection for actuating said link to vary the fuel and air supply in predetermined relation throughout the range of engine speeds, and an altitude compensating mechanism including a manually operable member, a pivoted element operable in its pivoting movement upon a part of said fuel control means to variably adjust the movement of said shiftable element by said fuel control means with relation 25 to the corresponding movement of said air control valve.

10. Apparatus of the character described comprising, in combination, an air intake for an internal combustion engine, an air intake valve 40 having a supporting shaft and an actuating arm, a fuel pump for supplying fuel to the engine cylinders, fuel control means for varying the fuel output of said pump including a shiftable element, a shaft, a cam supported on said shaft for operating said shiftable element, and an arm

on said shaft, a link connecting said arms and a manually operable accelerator connection for actuating said link to vary the fuel and air supply in predetermined relation throughout the range of engine speeds, and altitude compensating 5 mechanism including a manually operable member, a pivoted element and a slidable element, said pivoted element being connected to said manually operable member for movement about its pivot by said member, and said pivoted element being operable in its movement to impart sliding movement to said slidable element, and means operable upon a part of said control means by said slidable element in its movement to variably adjust the movement of said shiftable element 10 by said fuel control means with relation to the corresponding movement of said air control valve.

11. In combination with the air intake of an internal combustion engine, an air intake valve 20 having a supporting shaft and an actuating arm, a fuel pump for supplying fuel to the engine cylinders, fuel control means for varying the fuel output of said pump including a shiftable element, a shaft, a member supported on said 25 shaft for operating said metering valve, and an arm on said shaft, a link connecting said arms, a manually operable accelerator connection for actuating said link to vary the fuel and air supply in predetermined relation throughout the range 30 of engine speeds, and an altitude compensating mechanism including a manually operable member, a pivoted element and a slidable element mounted for movement longitudinally of said cam-supporting shaft, one of said elements being 35 connected to said manually operable member for actuation thereby and the other of said elements being actuated by said one element, said other of said elements being operable on a part of said fuel control means to vary the control movement of said shiftable element by said control means with respect to the corresponding movement 40 of the air control valve.

CARL F. HIGH.
